UNITED STATES PATENT OFFICE.

WILFRID LUMLEY, OF CONNEAUT, OHIO, ASSIGNOR TO GENERAL ELECTRIC COMPANY,
A CORPORATION OF NEW YORK.

ILLUMINATING APPARATUS.

1,156,537.

Specification of Letters Patent. Patented Oct. 12, 1915.

Application filed April 22, 1913. Serial No. 762,842.

To all whom it may concern:

Be it known that I, WILFRID LUMLEY, a citizen of the United States, residing at Conneaut, in the county of Ashtabula, State 5 of Ohio, have invented certain new and useful Improvements in Illuminating Apparatus, of which the following is a specification.

My invention relates to illuminating apparatus, and especially to apparatus of the glass bowl illuminator type employed for indirect and semi-indirect lighting. My invention not only makes it possible for such apparatus to be built in sizes which were 10 heretofore out of the question and allows its esthetic effect and its illuminative efficiency and more practical qualities to be improved and enhanced, but also greatly facilitates and cheapens its manufacture and 15 makes it easy to execute repairs in cases in which they were formerly either quite impossible or very expensive. Other advantages obtainable in connection with the invention will become apparent in the following description of a particular embodiment. It is to be understood, however, that while my invention extends to the particular form of apparatus described and to 20 many of its specific features and details, 25 which are of especial importance on account of specific advantages, yet the invention is not limited to this apparatus and its details, but can be otherwise carried out and applied.

30 In the accompanying drawings, Figure 1 is a side elevation of the apparatus, a portion being broken away and removed in order that certain structural features may be visible; Fig. 2 is a partial plan view, various parts being omitted to avoid confusion; Fig. 3 is an exterior detail view illustrating the configuration and relative arrangement of certain parts; and Fig. 4 is a fragmentary section at a surface indicated by the line 35 4—4 of Fig. 3.

It will be seen that the apparatus shown 40 comprises a bowl structure which is adapted to be suitably mounted or suspended and to contain one or more sources of light (as, for example, a number of incandescent lamps), and is intended to throw a portion of the light upward to the ceiling of the room in which it is used so that the light 45 may be reflected downward in such a manner that a more or less uniform, even, diffuse

illumination will be obtained. When illuminators of this type are made of glass and according to present ordinary practice, it is found practically almost impossible to produce a bowl substantially over two feet in diameter,—or, if such a bowl be made, to temper it so as to prevent it from remaining in a condition of internal stress that would render it liable to go to pieces when in use with serious consequences to persons near it 60 at the time. Such glass illuminators are therefore limited to about the size above mentioned, and even when of this size they are very expensive and quite difficult to make and handle. When the illuminators are 65 made in accordance with the mode of construction hereinafter set forth, however, such difficulties as these are entirely overcome, and within the range of what will in practice ever be desired limitations as to size no 70 75 longer exist.

Referring first to Figs. 1 and 2, it will be seen that the inclosure or bowl structure as a whole is built up out of a number of relatively small pieces. As here shown, a unitary integral piece 1 of glass or other similar or suitable material (itself shown as having the form of a bowl more or less nearly or exactly similar to the one piece bowl illuminators at present in ordinary use) 80 forms the bottom or "base" of the structure, as it were, and the portion above this is composed of a number of pieces of glass or the like of convenient size which to distinguish them from the bowl piece 1 may 85 be referred to as lamellæ or shingles. As shown, a number of such pieces are mounted and arranged in a row or tier 2 along the upper edge of the bowl piece so as to form an upward extension of its wall 1; and if 90 a bowl of larger size than this gives is required, the superstructure is further extended upward by means of additional more or less nearly horizontal rows 3 and 4 of such pieces, as also shown. In the construction 95 shown, the upper edges of the shingle pieces in a row overlap the lower edges of those in the row above it,—the bowl 1 overlapping the lower edges of the pieces in the lowermost row 2,—and the pieces in each row 100 also overlap at their adjacent edges (Figs. 2, 3, and 4). With such an arrangement and a suitable design of the pieces, the fact that the bowl is not all one piece need not, especially if the material employed is opaque 105 110

or semi-opaque, be noticeable or even observable, and the overlapping pieces may be made to blend in a harmonious general scheme of ornamentation of great variety of detail and so become a means of enhancing the esthetic appearance of the bowl rather than the reverse. To prevent light from within the bowl from shining out at the junctions of the pieces and to at least lessen the possibility of breakage from their jar-ring against one another, strips 5 of cloth or other fabric may be interposed between the overlapping edges; for example, such strips 5 may be secured along the underlying edges of each shingle piece by means of shellac (Fig. 4). As shown in Figs. 2, 3 and 4, radially extending edges of the pieces in a row are so formed that each piece is adapted to overlap the piece at one side of it and to lie behind the piece at the other side of it, so that in this particular structure the general resemblance of the pieces to shingles on a roof extends even to an exact similarity of arrangement as regards both the several rows and the pieces in each row. The form and configuration of the shingle pieces in row 2 are shown in Figs. 3 and 4, and that of those in row 4 in Fig. 2. The other shingle pieces are similar to these, but are merely shown somewhat diagrammatically to avoid confusion. It will, of course, be understood that the design and the relative arrangement of the pieces can be varied according to the exigencies of the particular case and the scheme of ornamentation employed.

The securing of the various "shingle" pieces together and to the bowl piece 1 can best be accomplished by attaching all the pieces to a suitable interior supporting structure, which may also serve for the mounting of the incandescent lamps within the bowl and for the attachment of the means whereby the illuminator is supported. In the construction shown, the interior supporting structure comprises a framework made up of annular metallic members or rings 6, 7, 8 and 9 joined together by radially extending members or braces 10. The parts 10, it will be seen, are composed of flat strips or bars curved in conformity with the general form of the illuminator and bent at suitable intervals to receive the rings. As shown, each of the parts 10 comprises two such strips, one of which lies beneath the rings and the other of which lies above the rings; and screws or screw bolts 11 extending through the strips serve to clamp the rings between them. The shingles of the several rows 2, 3, and 4, it will be seen, are secured to the several rings 6, 7, 8, and 9 near their upper and lower edges, the arrangement being such that the members 6, 7, 8 and 9 fall near the overlapping upper and lower edges of the shingles of adjacent rows. The bowl piece 1 may be secured to the lowermost ring

6 in very much the same way (now presently to be described) that the shingle pieces are secured; or it may be secured to a part 12 (similar to the braces 10 and, as shown, continuous with two of them) extending diametrically across the lower ring 7 by means of a rod 13 extending down from this part 12 through a hole at the center of the bowl piece 1 and having an ornamental knob 14 screwed on its lower ends, or in both these ways, as shown.

In addition to the framework, the interior supporting structure shown comprises a number of double footed approximately U shaped clips, brackets, or hangers 15 which serve as securing means for the attachment of the pieces to the rings 6, 7, 8, and 9. The hangers 15 shown consist of suitably bent strips of metal, and they are sprung open and slipped over the ring member 6, 7, 8, and 9 so that the latter rest in their bends. If it be deemed advisable, screw bolts 16 may be used as shown to secure and clamp some or all of the hangers 15 on the rings. For directly securing the pieces to the hangers 15 are employed fasteners 17 more or less similar to the ordinary "cotter-pin" binders that are used for fastening papers together. The fasteners 17 may be inserted through holes 18 in the pieces near their upper and lower edges and in the feet of the hangers 15 and their ends bent apart in the ordinary manner, washers 19 being preferably used between the heads of the fasteners 15 and the surface of the pieces, and also, if thought advisable, under the bent over ends of the fasteners. In the arrangement shown, the outer ends of the fasteners 17 at the lower edges of the shingle pieces of each row are concealed by the upper edges of the shingles in the row beneath or by the upper edge of the bowl piece 1. As for any fastener ends that are not so concealed (as shown, the heads of those near the upper edges of the shingles), they and their washers may be silvered, for example, and made a feature of the exterior ornamentation; or, if the bowl be made of milk glass, opal glass, or some colored glass, they may be painted or enameled and colored to harmonize with the surrounding area; or they may even be embedded in the material of the shingles themselves or otherwise covered up so as to be invisible. As shown, the heads of these fasteners lie at the centers of annular bosses 20 which form part of the ornamentation of the bowl, and so are not prominent at all. The lamps 21 and their shades, it will be seen, are mounted in holders or sockets 22 of any desired or approved form, and the sockets 22 are mounted on brackets 23 which are secured to the radially extending braces 10 by screws or screw bolts 24. Only a few of these lamps 21 with their associated parts are shown in order that

the drawing may not be confused. The chains 25 which in the apparatus shown support the illuminator are secured to split collars 26 clamped on the next to the upper 5 ring by suitable screws.

The various advantages obtainable by such a construction as that above described will be apparent almost without remark. Not only can the illuminators be made in 10 much larger sizes than heretofore, not only is damage which the illuminator may receive from any ordinary accident limited by the many piece construction, and not only can such damage be cheaply remedied 15 by the replacement of a few pieces, but the manufacture of the illuminators is very much cheapened by reason of the fact that illuminators of any size that will in practice be required can be made up with the 20 same line of lower row pieces, so that the production of these pieces can be carried out on a very large scale and in the most economical manner. Even, indeed, when only a comparatively small number of 25 specially large illuminators are to be manufactured, a very considerable number of pieces of each pattern will be employed for the upper rows, so that the design and manufacture of this portion of the illuminator 30 can also be made relatively inexpensive.

What I claim as new and desire to secure by Letters Patent of the United States, is:—

1. An illuminator comprising an inner 35 ring, an annular inclosure surrounding the said ring and made up of a plurality of overlapping sections, and means carried by the said ring for supporting each of the said sections.
2. An illuminator comprising an inner 40 ring, an annular inclosure surrounding the said ring and made up of a plurality of

overlapping sections, and detachable means carried by the said ring for supporting each of the said sections.

45

3. An illuminator comprising an inner ring, an annular inclosure surrounding the said ring and made up of a plurality of overlapping sections, means carried by the said ring for supporting each of the said sections, and means for preventing the transmission of light at the junction of the said sections.

50

4. An illuminator comprising an inner ring, a pair of superposed inclosure members surrounding the said ring and supported thereby at their adjacent edges, each of said members comprising a plurality of separable sections, and a light source supported within the said inclosure members by the 55 said ring.

55

5. An illuminator comprising a bowl composed of a number of overlapping pieces of glass, an interior structure for supporting said pieces, and attachment means for securing said pieces to said structure comprising 65 fasteners extending through holes in said pieces and in portions of the supporting structure aforesaid.

65

6. An illuminator comprising a bowl composed of a number of pieces of glass, an interior framework for supporting said pieces, clips carried by said framework and having feet for the attachment of the pieces, and fasteners extending through holes in said 75 pieces and in said feet and serving to secure said pieces to said clips.

70

In witness whereof, I have hereunto set my hand this 17th day of April, 1913.

WILFRID LUMLEY.
